JOHN CARREER, OF SOUTHBURG, CONNECTICUT.

Letters Patent No. 85,211, dated December 22, 1868.

IMPROVEMENT IN POCKET-CUTLERY.

The Schedule referred to in these Letters Patent and making part of the same.

To all whom it may concern:

Be it known that I, JOHN CARREER, of Southbury, in the county of New Haven, and State of Connecticut, have invented a new Improvement in Pocket-Cutlery; and I do hereby declare the following, when taken in connection with the accompanying drawing, and the letters of reference marked thereon, to be a full, clear, and exact description of the same, and which said drawing constitutes part of this specification, and represents a section through the handle, the blade open.

This invention relates to an improvement in pocket or spring-cutlery, the object being to avoid the rivets generally used for securing the spring, and thereby make the knife more durable; and

The invention consists in forming a recess through the back of the handle, of a dovetail-form, and at a distance from the end, and forming, upon one end of the spring, a corresponding dovetail, which shall set into the recess formed in the back of the handle, and extending along the handle to beneath the blade, so that, when the blade is inserted above the spring, the spring is secure in its position, and cannot be removed, except by the removal of the blade, and this is done without the use of rivets or other security.

In order to the clear understanding of my invention, I will fully describe the same, as illustrated in the accompanying drawings.

This invention is designed more especially for handles in which the scale and back are formed from the same metal.

In the back I form a recess, as at C, and the end of the spring D, I form to correspond to the said recess, with a shoulder, as at a, to form a bearing or fulcrum for the spring, and the spring extending along beneath the blade, with a projection there formed, as at d, to set into a corresponding recess in the back, as fully shown in the drawing, a space being left between the spring and back, along its surface, between the shoulder a and recess d, so as to allow the depression of the spring.

The blade A is inserted into the handle, and pivoted in the usual manner, the spring operating, when the blade is turned, as in knives of common construction.

Having thus fully described my invention,

What I claim as new and useful, and desire to secure by Letters Patent, is—

The spring D, constructed as described, and secured to the back by a dovetail projection, C, and resting upon a shoulder, a', and combined and arranged with the blade, so as to operate in the manner specified.

JOHN CARREER.
